US0D1026173S

(12) **United States Design Patent** (10) **Patent No.:** **US D1,026,173 S**
(45) **Date of Patent:** **** May 7, 2024**

(54) **FAUCET**

(71) Applicant: **Zhejiang Aike Technology Co., Ltd,**
Zhejiang (CN)

(72) Inventor: **Genxing Zhao**, Zhejiang (CN)

(73) Assignee: **ZHEJIANG AIKE TECHNOLOGY CO., LTD**, Zhejiang (CN)

(**) Term: **15 Years**

(21) Appl. No.: **29/783,081**

(22) Filed: **May 11, 2021**

(30) **Foreign Application Priority Data**

Mar. 8, 2021 (CN) 202130122882.X

(51) **LOC (14) Cl.** **23-01**

(57) **CLAIM**

The ornamental design for a faucet, as shown and described.

DESCRIPTION

FIG. 1 is a perspective view of a faucet showing my new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof; and,

FIG. 7 is a bottom plan view thereof.

The broken lines illustrate portions of the faucet which form no part of the claimed design.

1 Claim, 7 Drawing Sheets
